DESIGN FOR A TROUBLE LAMP

Eric Siemers, Kalamazoo, Mich., assignor to Roscoe B. Lacey, Kalamazoo, Mich.

Application December 4, 1943, Serial No. 111,902

Term of patent 7 years

To all whom it may concern:

Be it known that I, Eric Siemers, a citizen of the United States, residing at Kalamazoo, in the county of Kalamazoo and State of Michigan, have invented a new, original, and ornamental Design for Trouble Lamp, of which the following is a specification, reference being had to the accompanying drawing, forming part thereof.

In the drawing:

I claim:

The ornamental design for a trouble lamp, as shown.

ERIC SIEMERS.
